UNITED STATES PATENT OFFICE

FRANK E. TWISS, OF TAUNTON, MASSACHUSETTS, ASSIGNOR OF FORTY ONE-HUNDREDTHS TO WILLIAM J. HOYE, OF SHELTON, CONNECTICUT

REMOTE CURTAIN CONTROL

Application filed September 21, 1929. Serial No. 394,332.

This invention relates to an electrically actuated mechanism for operating a window shade, particularly a window shade that is positioned in a difficultly accessible location as in the rear of an automobile of the coach or sedan types. The need for lowering the rear curtain shade of an automobile at night is very apparent to any motorist whose vision is confused by the glare of the headlights of machines following directly behind. To lower the curtain shade by hand even where it may be reached as in the case of a coupé would of necessity direct the attention of the driver from the road ahead and introduce an element of danger. Should the curtain shade be at some distance behind the driver he would of necessity be forced to stop the car or enlist the services of some person seated in the rear. By means of the mechanism which I hereinafter describe it is possible for the driver to operate the window shade in an up or down direction for any desired distance by simply touching a control switch accessibly and conveniently located.

It is an object of this invention to provide an electrically actuated device for operating a window shade which is simple in structure and reliable in operation.

A further object of my invention is to provide an electrically actuated device for lowering or raising a window shade any desired distance, which is particularly adapted to be used in conjunction with the rear window shade of any automobile, the control switch being conveniently positioned near the operator of the automobile.

A further object of my invention is to provide an electrically operated device for lowering or raising a window shade any desired distance which comprises two aligned solenoid coils with a common core therein, the ends of which are secured by a strand to the pintle of the curtain roller and is adapted to rotate the roller in a clockwise or counter-clockwise direction depending upon which coil is energized. A two circuit switch for energizing either coil is positioned near the operator.

Other objects and advantages will appear from the detailed description which follows

when read in conjunction with the accompanying drawing.

I attain these objects and advantages by means of the device illustrated in the accompanying drawing wherein:

Figure 1 is a view showing the rear window of an automobile of the closed type showing the device for lowering or raising the curtain or shade in operative position secured to the automobile body adjacent the window.

Figure 2 is a cross sectional view taken through line A—A of Figure 1 in the direction of the arrows showing the core in elevation.

Figure 3 is a detailed view showing the top end of the solenoid device with the strand attached to the core secured to the pintle of the curtain roller and showing the stop member at the top end for limiting the movement of the core.

Figure 4 is a diagrammatical view of the device.

Similar numerals refer to similar parts throughout the several views.

Referring to the drawing, the numeral 1 designates the curtain roller upon which the curtain or shade 2 is mounted in the usual manner. The curtain roller may be made of a solid or hollow cylinder and of any suitable material. At one end of the curtain roller is the short pintle 3 which is held by the bracket 4 of ordinary construction. At the other end a pintle 5 of much greater length projects into and is held by a bracket 6 within the housing 7 of the electrically actuated mechanism to be described. Guide strings 8 may be provided on each side of the window which thread through eye hooks 9 in the free end of the curtain. The window 10 of the automobile is shown as well as the top of the rear seat.

Disposed within the housing 7 is the actuator unit for operating the window shade. The unit comprises two aligned solenoid coils 12 and 13 which may be wound around a suitable metallic or fibrous tubing 15. The number of turns of wire forming each coil is not arbitrary in amount but should be sufficient to create a strong magnetic flux. Arranged within the coils is a thick cylindri-

cal core 14 of soft iron which is longer than either coil and projects into the second coil whereby it is only necessary to have one core. To the ends of the core 14 are attached small 5 resilient springs 16 and to these springs the ends of a strand are secured, the strand being threaded through a hole 18 in the pintle 5 and pass around a pulley 19 whereby the unwinding of the turns of the strand on one side of 10 the hole 18 cause a corresponding number of turns to be wound on the opposite side of the hole 18. In other words every unwinding incident to operating the curtain is accompanied by a winding which causes the curtain 15 to be always in condition for movement. The springs 16 are adapted to take up vibrations during travel on the road and also to absorb vibrations set up when the current is turned on momentarily when the curtain moves only 20 a slight distance. Stop members 20 are provided at each end of the aligned solenoids to limit the upward and downward movement of the core when the curtain has been fully wound or unwound. The stop members are 25 angular brackets one side being secured to the housing, the other side having a hole therein for the core and being spaced a short distance from the end of the solenoid coil. The springs 16 come in contact with the stop 30 members to arrest the movement of the core.

The device is mounted within a housing and secured to a base plate 21 which may be secured to the automobile body by screws which are invisible from without. The cover member 35 7 may be arranged to stay in place by a force fit as shown in Figure 2.

In Figure 4 the schematic arrangement of the electrical circuits is shown. Each of the solenoid coils 12, 13 is grounded at one end 40 at 22 the other end being connected to a two circuit switch S. A source of electricity is shown at B which may be the usual storage battery having one terminal grounded at 23, the other terminal being connected to switch 45 S. It is apparent from the diagram that there are two independent circuits and that the two solenoids act independently of each other. The core 14 is of sufficient length to project into the second coil and by reason of 50 the flux set up in the coil the core may be made to reciprocate. A slight tap on the switch will cause the core, and correspondingly the curtain to move a slight distance. The switch should be placed near the driver and 55 legends or characters such as D and U may be used on the switch to indicate the direction of movement of the curtain.

A suitable fuse or thermostatic device F may be interposed in the circuit as shown in 60 Figure 4 as a fool-proof means to prevent damage to the coils.

All that has been said above in the description of my preferred embodiment is offered by way of illustration and not limitation. I 65 do not wish to be limited to the exact struc-

ture of the preferred embodiment shown and described, or to any particular material used in the construction of parts, or to the design of parts, but desire protection as against any variations in structure or substitution of equivalents which utilize the principle of my invention and fall within the purview of my invention and are within the spirit and scope of the following claims:—

The invention having been set forth what is claimed as new and useful is:

1. A remote curtain control device comprising a roller for the curtain, electrical means external of said curtain roller for rotating said curtain roller, said electrical means comprising two separately acting solenoid coils having a traveling core means therein, and means connecting said core means and said roller to impart rotation to said roller.

2. A remote curtain control device comprising a roller for the curtain, said curtain roller being mounted for rotation, electrically actuated means adjacent one end of said curtain roller and disposed thereto at substantially a right angle, said means being capable of rotating said curtain roller, said electrical means comprising two separately acting solenoid coils having a traveling core means therein, and means connecting said core means and said roller to impart rotation to said roller.

3. A device for shifting a curtain for a distance comprising a curtain roller mounted for rotation, an exterior electrically operated means at one end of said curtain roller, pintle members on said curtain, one of said pintle members having a strand connected thereto, said strand being capable of movement by said electrically operated means whereby the curtain rollers is rotated, and a switch means for operating said electrically operated means.

4. A device for shifting a curtain or shade from a distance comprising a curtain roller mounted for rotation, an electromagnetic device adjacent one end of said curtain roller, a travelling iron core within said electromagnetic device, means connecting the ends of said travelling iron core with the end of said curtain roller, a source of current, a switch conveniently positioned, whereby the closing of the circuit causes the travelling core to actuate the curtain roller.

5. A remote control device for winding and unwinding a curtain or shade comprising in combination with one end of a rotatably mounted curtain roller, an electromagnetic device composed of two aligned separately acting solenoid coils, a common travelling core therein, means passing from the ends of said core to one end of said curtain roller, a source of current, a two circuit switch conveniently positioned for energizing either

coil whereby the curtain is wound or unwound.

6. A remote control device for winding or unwinding a curtain or shade comprising in combination a curtain roller, and an elongated base plate, said roller having a long pintle at one end, one end of said base plate being disposed near the end of said curtain roller having the long pintle, two separately acting 10 solenoid coils mounted on said elongated base, core means within said coils, means leading from the ends of said core means to the said long pintle, a source of current, and a switch for energizing either solenoid coil.

15 7. A remote control device for winding or unwinding a curtain or shade comprising in combination a curtain roller mounted for rotation, said curtain roller having a long pintle at one end for receiving windings, an electromagnetic device for actuating said curtain 20 roller comprising an elongated base plate adjacent one end of said curtain roller, a bracket on said base plate for receiving said pintle, said pintle having a hole therein, two 25 separately acting solenoid coils, a common core traveling therein, strand means connected to the ends of said core and threading through said opening, a portion of said strand means being wound on each side of the 30 opening a sufficient number of turns to move the curtain shade the desired distance.

8. A remote control device for winding or unwinding a curtain or shade comprising in combination a curtain roller mounted for 35 rotation, said curtain roller having a long pintle at one end for receiving windings, an electromagnetic device for actuating said curtain roller comprising a housing disposed substantially at a right angle to said curtain 40 roller, a bracket within said housing for receiving said pintle, two separately acting solenoid coils, a traveling core within said solenoid coils, a strand connecting said core and said long pintle, and stop means at each 45 end of said coils to limit the travel of the core.

9. A remote control device for winding or unwinding a curtain or shade comprising in combination a curtain roller mounted for 50 rotation, an electromagnetic device adjacent one end of said curtain roller comprising a housing, said roller having a pintle of sufficient length to extend into said housing, a 55 support within said housing for said pintle, separately acting aligned solenoid coils disposed within said housing, a core traveling therein, a strand means connecting said core and said pintle, and means at each end of said coils for guiding said strand means and 60 limiting the travel of said core.

10. A remote control device for winding or unwinding a curtain or shade comprising in combination a curtain roller mounted for 65 rotation, two separately acting aligned solenoid coils having a common core disposed

adjacent one end of said curtain roller, a strand means connecting said core with one end of said curtain roller, guiding means therefor adapted to delimit the travel of said core, and equalizing resilient means on said strand. 70

Signed at Providence, in the county of Providence, State of Rhode Island, this twelfth day of September, 1929.
